REVERSING MECHANISM

William J. Pearmain, Racine, Wis., assignor to
Twin Disc Clutch Company, Racine, Wis., a
corporation of Wisconsin

Application April 16, 1934, Serial No. 720,677

6 Claims. (Cl. 74—377)

My invention relates to a reversing mechanism provided with an improved clutch device for effecting a transmission of power between driving and driven shafts and is more particularly concerned with providing a mechanism of this character for marine service.

In marine power installations, particularly those employing internal combustion engines, it is necessary to step down the revolution speed of the engine to a point that is satisfactory for the efficient operation of the propeller. Ordinarily, this reduction is effected through a suitable arrangement of gearing which includes a reversing device. The reduction features of this invention, however, may be omitted wherever desired, as it simply constitutes an ancillary phase of my improved device.

The present application is a continuation in part of my copending application for a reverse and reduction mechanism, Serial No. 707,093, filed January 18, 1934, and differs therefrom as a matter of disclosure in a reduction in the number of bearings employed to transmit the thrust of the mechanism. The original application is more particularly concerned with the control feature of the mechanism, including the application of spring pressure to the clutches, while the present application relates to the arrangement of the component gears, clutches and thrust bearings.

One object of my invention is to devise a mechanism which incorporates direct and reverse driving gears whose selection is determined by the operation of disc clutches, one each for the direct and reverse drives, and which are spring-loaded and locked in their respective driving positions by the operation of throwing them into engagement, each clutch being free to assume positions out of engagement when in non-driving position.

A further object is to devise a mechanism as set forth above which employs a pair of multiple disc clutches, one set of discs for each clutch being carried by a shiftable member common to both clutches, and this member being positively driven by the main power source.

A further object is to devise a reverse and reduction mechanism employing a pair of shafts, one of which is driven by the main power source and has keyed thereto the aforesaid shiftable member in addition to a pair of freely rotatable gears located on opposite sides of the member, and the other shaft has a pair of gears keyed thereto, one of the keyed gears meshing with one of the freely rotatable gears and the remain-

ing gears separately meshing with an internal gear connected to the driven shaft.

A further object is to devise a mechanism of the character indicated in which a single thrust bearing is employed by the direct and reverse driving gears, respectively, in conjunction with a thrust bearing common to both clutches to transmit the drive through the mechanism.

A further object is to devise a mechanism controlled by twin clutches in which the gear thrust bearings encircle hubs connected to the gears and are mounted in cages forming a part of the enclosing housing and preferably located between the associated gear and clutch.

These and further objects of my invention will be set forth in the following specification, reference being had to the accompanying drawings, and the novel means by which said objects are effectuated will be definitely pointed out in the claims.

In the drawings:

Figure 1 is a sectional elevation of my improved mechanism as viewed along the line 1—1 in Fig. 4, looking in the direction of the arrows.

Fig. 2 is a section along the line 2—2 in Fig. 1, looking in the direction of the arrows, and showing the relation of the shifting arms to the clutch devices.

Fig. 3 is a section along the line 3—3 in Fig. 1, looking in the direction of the arrows, and showing the relation of the internal gear on the driven shaft to the direct and reverse gears forming part of the principal mechanism.

Fig. 4 is an end view, partly in section, of my improved mechanism, looking in the direction of the arrow 4 in Fig. 1.

Fig. 5 is an enlarged view of the operating device for the mechanism, as viewed in the direction of the arrow 5 in Fig. 4.

Fig. 6 is an enlarged sectional view of the clutch portion of the mechanism, as viewed in Fig. 1, the two clutches being shown in neutral position.

Fig. 7 is a view similar to Fig. 6, but showing the direct drive clutch in engagement and the manner in which the same is held in this position.

Referring to Fig. 1, the numeral 10 designates a shaft which may be considered as the main power source and which has a flywheel 11 attached to the end thereof. The flywheel is internally bored from the right face thereof, as viewed in Fig. 1, and within this bore, there is located a spider or disk 12 which is bolted to the flywheel and is also fixed to one end of a shaft

13 that will be regarded as the driving shaft of the mechanism. The shaft 13 extends across the interior of a housing 14 and it is intermediately provided with an enlarged, splined portion 15 (see Fig. 6) which has fitted thereon a pair of drums 16 and 17 whose open ends face in opposite directions. These drums are fastened together by screws 18 in order to provide a common, shiftable member which is adapted for axial movement along the portion 15, but partakes of the rotary movement of the shaft 13.

The drum 16 carries a plurality of fixed discs 19 which are arranged in alternating relation to a plurality of similar discs 20 supported on a hub 21. This hub is freely rotatable on a bearing sleeve 22 which encircles the portion of the shaft 13 to the right of the enlarged portion 15 and it is also fixedly connected to a pinion 23 which meshes permanently with an internal gear 24 (see Fig. 1) that is fastened to a driven shaft 25 which projects without the housing 14 and may be suitably connected to a propeller or other type of shaft. As shown in Fig. 1, the pinion 23 is disposed above, or to one side of, the axis of the shaft 25, thereby providing space for an additional pinion to transmit a reversing drive to the shaft 25, as hereinafter described.

A thrust bearing 26 encircles the hub 21 with its inner race located in a channel 27 defined by a shoulder 28 formed on the hub 21 and a shoulder 29 formed on the gear 23. The outer race of the same bearing is fixedly retained within a cage 30 that is provided on a web 31 that extends upwardly from the bottom of the housing 14. The bearing 26, not only resists a portion of the thrust of the mechanism during direct drive, but it also operates as a support for the right end of the driving shaft 13.

The drum 17 also supports a plurality of friction discs 32 which are arranged in alternating relation to a plurality of friction discs 33 that are carried by a hub 34 and these last named discs constitute the reversing clutch of the mechanism. As with the direct drive clutch, the hub 34 is freely rotatable upon a bearing sleeve 35 that is mounted on that portion of the shaft 13 to the left of the enlarged portion 15 (see Fig. 6) and it is also fixedly connected to a pinion 36. A thrust bearing 37, similar to the bearing 26, has its inner race located in an annular channel 38 formed around the hub 34 and defined by a shoulder 39 on the hub and also by a shoulder 40 formed on the gear 36. The outer race of the same bearing is fixedly retained within a cage 41 forming a part of a web 42 which extends upwardly from the bottom of the housing 14. The bearing 37 serves as a support for the left end of the driving shaft 13.

The pinion 36 is in constant mesh with a gear 43 fixedly attached to one end of a countershaft 44 that is rotatably mounted in bearings 45 and 46 that are carried in the webs 42 and 31, respectively. The opposite end of the shaft 44 has fixedly connected thereto a gear 47 that is in permanent mesh with the internal gear 24 and located on the opposite side of the axis of the shaft 25 from the pinion 23, thus providing the maximum space for the reception of the gear 47 and pinion 23.

The inner race of a ball bearing 48 is clamped between the adjacent faces of the drums 16 and 17 by the screws 18 (see Fig. 6) and encircling and fixedly connected to the outer race of the same bearing is a yoke 49 which is provided with a pair of laterally extending trunnions 50 which

project from opposite sides thereof (see Fig. 2). A pair of arms 51 are pivotally mounted on the trunnions 50, respectively, and the lower end of each arm is pivotally supported upon a pin 52 that is carried by the housing 14. The upper ends 5 of the arms 51 are pivotally connected to stub arms 53, respectively, which project laterally in opposite directions from a block 54 (see Figs. 2 and 6) whose movements to and fro, as herein-after described, effect a rocking of the arms 51 10 on their respective pivots to thereby throw either of the aforesaid clutches into engagement. In the relative positions shown in Fig. 6, these clutches occupy neutral or non-driving positions.

A bar 55 (see Fig. 7) is slidably mounted in 15 the block 54 with its ends projecting on opposite sides thereof, the central portion of the bar being enlarged as at 56 to thereby form a pair of annular shoulders 57 with the reduced extremities 20 of the bar. The left end of the bar, as viewed in Fig. 7, has mounted thereon a nut 58, while the opposite end of the bar has attached thereto a block 59. A coil spring 60 encircles the bar between the nut 58 and a washer 61 which, in the position shown in Fig. 6 is seated both against 25 the left face of the block 54 and the left shoulder 57. A similar coil spring 62 encircles the bar between the block 59 and a like washer 61 which is seated against the right face of the block 54. 30 These springs are of equal strength.

The block 59 is pivotally mounted upon an eccentric pin 63 that forms part of a rock shaft 64 (see Fig. 4) which extends through the casing 14 and has attached to the outer end thereof a gear 65. This gear meshes with a sector gear 66 that 35 is provided with a band 67 clamped to an operating shaft 68. The latter shaft is rotatably mounted in the housing 14 and is provided with two exposed extremities 69 that are located on opposite sides of the vertical center line of the 40 housing, as viewed in Fig. 4. The operating handle for the mechanism may therefore be disposed in the most convenient position, depending upon the environment. Offset from the sector gear 66 and integrally formed therewith are 45 a pair of stops 70 and 71 which are located on opposite sides of the shaft 64 and which are intended to engage, as hereinafter described, with a reduced portion 72 of the shaft 64 that projects beyond the gear 65.

The operation of my improved reversing mechanism will now be described. Referring to Figs. 1 and 6, it will be assumed that the shaft 10 is rotating at some determined speed, which rotation is in turn transmitted to the driving shaft 13 55 by the spider 12, and that the shifting arms 51 occupy the neutral positions shown in Fig. 6. In this position of the indicated parts, it will be noted that, while the clutch drums 16 and 17 are rotating with the shaft 13, the shifting arms and 60 the parts which operate the same permit this rotation by reason of the association of the yoke 49 with the outer race of the ball bearing 48.

If now it is decided to transmit a direct or forward drive to the driven shaft 25, the operating 65 shaft 68 will be rocked in a counter-clockwise direction, as viewed in Fig. 6 to thereby impart a movement of the eccentric pin 63 in a clockwise direction. This movement pulls the bar 55 through the block 54 and begins to compress the spring 60. When this spring has been sufficiently compressed to effect a movement of the shifting arms 51 toward the right, as viewed in Fig. 6, the latter movement will take place with a consequent shifting of the friction discs 19 into en- 75

gagement with the discs 20. The limit of movement of the eccentric pin 63 is determined by the engagement of the stop 70 with the shaft portion 72 and, at this time, the eccentric pin will 5 be slightly below the line joining the centers of the shaft 64 and the stub arms 53, thereby locking the spring 60 in its compressed position against its otherwise tendency to release and insuring that the pressure of the spring will maintain the aforesaid friction discs in engagement.

During the foregoing compression of the spring 60, it may be noted from Fig. 7 that the spring 62 remains uncompressed, since the right hand washer 61 moves concurrently with the block 59 10 so that the distance between these elements remains unchanged.

With the right hand clutch in engagement, the drive from the shaft 10 is transmitted through the flywheel 11, spider 12, driving shaft 13, and 20 the right hand clutch comprising the discs 19 and 20, hub 21, and pinion 23 to the internal gear 24 and then to the driven shaft 25.

If now it is desired to reverse the drive through the mechanism, the operating shaft 68 will be 25 rocked in a clockwise direction to thereby shift the eccentric pin 72 above and to the opposite side of the shaft 64 from that illustrated in Fig. 7. During this movement, the compression of the spring 60 will be released, and a spring 62 will 30 be compressed, and the limit of this movement will be determined by the engagement of the stop 71 with the shaft portion 72. With the left hand clutch in engagement, the right hand clutch is thereby thrown out of engagement, thus leaving 35 the pinion 23 to rotate freely on the shaft sleeve 22, and the drive from the shaft 10 will then occur through the following parts, the flywheel 11, spider 12, driving shaft 13, left hand clutch comprising the discs 32 and 33, pinion 36, gear 43, 40 countershaft 44, and pinion 47 to the internal gear 24 and then to the driven shaft 25.

The foregoing mechanism may be embodied in an arrangement that is quite compact and in which the loading springs for the clutch are compressed by the operation of throwing the clutches into engagement, the springs thereafter being held against their own tendency to release. Further, because the respective clutches are engaged by the simple operation of loading the respective 45 springs which in turn are always under the control of the operator, the clutches may be thrown into engagement free of any tendency to grab or jerk. Also, the clutches being spring-loaded, will automatically compensate for any slight wear 50 that may take place in operation.

The driving shaft 13 of the mechanism is not only supported in the housing 14 by the bearings 26 and 31, but these bearings, in conjunction with the bearing 48, also serve to take the thrust of 55 the mechanism during direct and reverse drives, respectively. This arrangement, therefore, represents an advance over the comparable structure shown in the foregoing application because of the substantial halving of the number of bearings required. Moreover, the use of ball bearings to 60 take the thrust entirely eliminates any necessity for rotating, clutch operating mechanism which is a further reason for the compactness of construction. The mechanism above described is 65 not restricted to the use of multiple disc clutches, but is also obviously capable of adaptation to cone and single plate clutches and other types.

I claim:

1. In reversing mechanism, the combination of 70 75 a housing, a driving shaft mounted in the hous-

ing and adapted for connection to a power source, a driven shaft, a gear fixed to the driven shaft, and means for operating the driven shaft in opposite directions comprising a pair of gears freely rotatable on the driving shaft, one of which is in constant mesh with the driven shaft gear, a thrust bearing engaging each of the freely rotatable gears, respectively, and mounted in the housing, a counter shaft, a pair of gears fixed on the counter shaft, one of which meshes with the other of the freely rotatable gears and the other with the driven shaft gear, a member shiftable on and rotatable with the driving shaft between the freely rotatable gears, a third thrust bearing 10 engaging the member, a pair of clutches connecting the member with the freely rotatable gears, respectively, and means for shifting the member to engage either of the clutches, the third thrust bearing coacting with the other thrust bearings, 15 respectively, to take all thrust loads during direct and reverse drives, respectively, whereby not more than two bearings are subjected to thrust in either direction.

2. In reversing mechanism, the combination of 20 a housing, a driving shaft supported in the housing and adapted for connection to a power source, a driven shaft, a gear fixed to the driven shaft, and means for operating the driven shaft in opposite directions comprising a pair of gears freely 25 rotatable on the driving shaft, one of which is in constant mesh with the driven shaft gear, a counter shaft, a pair of gears fixed on the counter shaft, one of which meshes with the other of the freely rotatable gears and the other with the driven shaft gear, a member shiftable on and 30 rotatable with the driving shaft between the freely rotatable gears, a thrust bearing engaging the member and supported in the housing, a pair of spring-loaded clutches connecting the member with the freely rotatable gears, respectively, a 35 thrust bearing engaging each of the freely rotatable gears, respectively, between the gears and associated clutches, respectively, each of the last-named bearings being mounted in the housing, and means for shifting the member to engage 40 either of the clutches, the first named thrust bearing coacting with the other thrust bearings, respectively, to take all thrust loads during direct and reverse drives, respectively, whereby not 45 more than two bearings are subjected to thrust in either direction.

3. In revering mechanism, the combination of 50 a housing, a driving shaft adapted for connection to a power source, a driven shaft, a gear fixed to the driven shaft, and means for operating the driven shaft in opposite directions comprising a pair of gears freely 55 rotatable on the driving shaft, one of which is in constant mesh with the driven shaft gear, friction discs connected for rotation with each of the freely rotatable gears, a counter shaft, a pair of gears fixed on the counter shaft, one of which meshes with the other of the freely rotatable gears and the other with the driven shaft gear, a casing 60 shiftable on and rotatable with the driving shaft between the freely rotatable gears, two sets of friction discs carried by the casing adapted to cooperate with the first-named friction discs, respectively, the cooperating discs constituting a 65 pair of clutches, means for shifting the casing to engage either of the clutches, cages formed in the housing encircling the hubs of each of the freely rotatable gears and casing between the sets of discs, respectively, and thrust bear- 70 75

ings mounted in each of the cages and engaging the associated hubs and casing.

4. In reversing mechanism, the combination of a driving shaft adapted for connection to a power source, a driven shaft, a gear fixed to the driven shaft, means for operating the driven shaft in opposite directions comprising a pair of gears freely rotatable on the driving shaft, one of which is in constant mesh with the driven shaft gear, a counter shaft, a pair of gears fixed on the counter shaft, one of which meshes with the other of the freely rotatable gears and the other with the driven shaft gear, a member shiftable between the freely rotatable gears, a pair of clutches connecting the member with the freely rotatable gears, respectively, and means for shifting the member to engage either of the clutches.

5. In reversing mechanism, the combination of a housing, a driving shaft mounted in the housing and adapted for connection to a power source, a driven shaft, a gear fixed to the driven shaft, and means for operating the driven shaft in opposite directions comprising a pair of gears freely rotatable on the driving shaft, one of which is in constant mesh with the driven shaft gear, a thrust bearing engaging each of the freely rotatable gears, respectively, and mounted in the housing, a counter shaft, a pair of gears fixed on the counter shaft, one of which meshes

with the other of the freely rotatable gears and the other with the driven shaft gear, a member shiftable on and rotatable with the driving shaft, a third thrust bearing engaging the member and shiftable therewith, a pair of clutches connecting the member with the freely rotatable gears, respectively, and means for shifting the member to engage either of the clutches, the third thrust bearing coacting with the other thrust bearings, respectively, to take all thrust loads during direct and reverse drives, respectively, whereby not more than two bearings are subjected to thrust in either direction.

6. In reversing mechanism, the combination of a driving shaft adapted for connection to a power source, a driven shaft, a gear fixed to the driven shaft, means for operating the driven shaft in opposite directions comprising a pair of gears freely rotatable on the driving shaft, one of which is in constant mesh with the driven shaft gear, a counter shaft, a pair of gears fixed on the counter shaft, one of which meshes with the other of the freely rotatable gears and the other with the driven shaft gear, a shiftable member, a pair of clutches connecting the member with the freely rotatable gears, respectively, and means for shifting the member to engage either of the clutches.

WILLIAM J. PEARMAIN.
